UNITED STATES PATENT OFFICE.

ANTONIO SERINO, OF ROXBURY, MASSACHUSETTS.

DESIGN FOR A SHOE.

Application filed September 28, 1922. Serial No. 3,839. Term of patent 3½ years.

To all whom it may concern:

Be it known that I, ANTONIO SERINO, a subject of Victor Emmanuel III, King of Italy, residing at Roxbury, in the county of Suffolk and Commonwealth of Massachusetts, have invented a new, original, and ornamental Design for a Shoe, of which the following is a specification, reference being had to the accompanying drawing, forming part thereof.

The figure is a side elevation of a shoe showing my new design.

I claim:—

The ornamental design for a shoe, as shown.

ANTONIO SERINO.
